UNITED STATES PATENT OFFICE.

JOHN M. PRATT, OF WINNIPEG, MANITOBA, CANADA.

DESIGN FOR A DOLL.

60,811.

Specification for Design.

Patented Apr. 11, 1922.

Application filed June 25, 1921. Serial No. 480,455. Term of patent 14 years.

To all whom it may concern:

Be it known that I, JOHN M. PRATT, a subject of the King of Great Britain, residing at Winnipeg, in the Province of Manitoba, Canada, have invented a new, original, and ornamental Design for Dolls, of which the following is a specification, reference being had to the accompanying drawings forming part thereof, wherein is shown a perspective view of the doll.

I claim:

The ornamental design for a doll as shown.

JNO. M. PRATT.
